ALBERT H. DE VOE, OF WESTFIELD, NEW JERSEY, ASSIGNOR TO THE SINGER MANUFACTURING COMPANY, A CORPORATION OF NEW JERSEY.

HEMMING ATTACHMENT FOR SEWING-MACHINES.

1,271,291.

Specification of Letters Patent.

Patented July 2, 1918.

Application filed September 20, 1917. Serial No. 192,265.

To all whom it may concern:

Be it known that I, ALBERT H. DE VOE, a citizen of the United States, residing at Westfield, in the county of Union and State 5 of New Jersey, have invented certain new and useful Improvements in Hemming Attachments for Sewing-Machines, of which the following is a specification, reference being had therein to the accompanying drawings.

This invention relates to sewing machine attachments particularly of the kind known as hemmers. In hemming material which is cut on a 15 convexed curve, the overturned margin being of greater length than the underlying body portion, it is liable to kink or fold and thereby mar the appearance of the finished product. It is an object of this invention to provide against such a defective appearance of the product by distributing the fullness among the stitches securing the hem down.

The invention consists essentially of a 25 separating arbor-like member arranged in advance of the needle-hole with its end portion which is nearest the needle substantially abreast of the front wall defining the needle-hole and with the highest part of this 30 same end portion at a higher elevation than the lowest surface of the presser-foot under which the overturned margin of the hem is adapted to pass so that the turned margin of the hem will cross the needle-path at an 35 inclination.

The invention in its preferred form is 40 illustrated in the accompanying drawings, in which Figure 1 is a side elevation of a combined presser-foot and hemmer. Fig. 2 is a plan view of the same. Fig. 3 is a 45 cross-section on the line *a*—*b*, Fig. 2. Fig. 4 is a cross-section on the line *c*—*d*, Fig. 2 and Fig. 5 is a detailed perspective of the 50 separating member and its spring.

In the embodiment of the invention illustrated in the drawing, the shank 1 of the presser-foot is provided at its lowest portion with a transverse rib 2 to which the correspondingly grooved foot portion 3 is 55 adjustably secured by means of the screw 4 tapped into the foot portion and passing through the elongated opening 5 in the shank. A needle-hole 6 through which the needle 6' passes is provided in the foot portion and it is elongated transversely *i. e.*,

in a direction across the line of seam formation.

In advance of the needle-hole the foot portion 3 is provided with a folding member 7 having a substantially vertical directing portion 8 and a curved and downwardly inclined deflecting surface 9 extending from a point slightly in front of the needle-hole to a point a greater distance in rear of the needle-hole. In advance of the needle-hole and 60 on the side thereof opposite to the folding member 7 the foot portion is provided with a supporting arm 10 drilled to receive the shoul- 65 dered pivot screw 11 which is tapped into a triangular-shaped block 12 constituting 70 a separating member about which an over- turned margin of material may be folded and held spaced from the underlying body portion of the material.

This separating member 12 has a down- 75 wardly and rearwardly inclined upper or top surface 13 which terminates in an end portion 14 located intermediate the upper and lower faces of the foot portion, imme- 80 diately adjacent the path of the needle, and substantially abreast of the wall defining the front of the needle-hole. Between the pivot screw 11 and the needle-hole 6 the separating block 12 is provided with a pin 15 whose axis is substantially parallel to that of the 85 pivot 11. A channel 16 is formed in the lower surface of the foot portion as shown and a spring 17 is clamped by a screw 18 in the channel with its free end bearing 90 yielding upward against the pin 15 which 95 is free to yield downwardly from the normal operating position shown in Fig. 1 until the pin 15 contacts with the lower wall of the clearance aperture 19 provided in the 95 arm 10 of the foot portion.

The folding member 7 may, if desired, be provided with a guard or ledge 20 secured in any suitable manner thereto, as by the screw 21, for preventing the material being operated upon working out under the fold- 100 ing member 7.

In using this device, which was especially designed for turning a hem on that portion of a toe-vamp which joins with the upper, the material is inserted over the guard or 105 ledge 20 and turned by hand so that it assumes the condition illustrated in Fig. 3. After a few stitches have been made the overturned margin will be in the condition 110 illustrated in Fig. 4 so that the needle will

penetrate it at an angle less than 90° and thereby the length of material between successive stitches will be greater in the overturned portion of the hem than in the underlying body portion. In this way it will be seen that the surplus material in hemming a curved edge will be distributed among successive stitches and prevented from causing a fold in the overturned margin of the hem.

5 By making the separating member yielding this action may be varied to suit different curvatures, the operative merely holding back on the work gripped between the feed-dog and the presser-foot and thus inclining it at such an angle that the separator 12 will be depressed sufficiently to suit the particular curvature of the edge being stitched.

10

15 The screw 4 and slot 5 permit of bodily and laterally adjusting the foot portion relative to the needle, whose path is fixed, and thereby of varying the distance of the stitching from the hem fold.

Having thus set forth the nature of the invention, what I claim herein is:—

20 1. In a sewing machine having stitch-forming mechanism including a needle, a presser-foot provided with a needle-hole, a hemmer having a separating member over which a turned margin of material may pass, said separating member terminating in an end portion immediately adjacent and in advance of the path of the needle, said end portion having its highest surface located at a higher elevation than the lowest part 25 of the presser-foot on the opposite side of the needle-hole whereby the overturned margin of a hem may be pierced by the needle at an inclination.

25 2. In a sewing machine having stitch-forming mechanism including a needle, a presser-foot provided with a needle-hole, a folding member for turning a margin of material on itself, said folding member having a directing wall merging into a deflecting 30 curved wall immediately adjacent the needle-hole, a separating member around which the overturned margin of a hem is adapted to be bent, said separating member having a downwardly and rearwardly inclined top 35 surface terminating in an end portion substantially abreast of the front of the needle-hole, said separating and folding members being spaced apart to define a channel in the lower surface of the presser-foot, and 40 said inclined top surface of the separating member being spaced above the lowest surface of the presser-foot in rear thereof in the direction of feed whereby the surplus material in the overturned margin of a hem 45 on a convexedly curved edge may be distributed.

50 3. In a combined hemmer and presser-foot provided with a needle-hole, a folding member at one side and in advance of the 55 needle-hole, a substantially parallel support-

ing arm at the opposite side and in advance of the needle-hole, a separating member yieldingly mounted on said arm in advance of the needle-hole, said separating member having an end portion located at a higher 70 elevation than the lowest surface of the presser-foot in rear thereof in the direction of feed.

4. In a combined hemmer and presser-foot provided with a needle-hole, a folding member at one side and in advance of the needle-hole, a substantially parallel supporting arm at the opposite side and in advance of the needle-hole, a separating member pivoted to said arm, means for holding said separating member in operative position with the highest part of its end portion above the lowest surface of the presser-foot under which the turned margin is adapted to pass.

5. In a combined hemmer and presser-foot provided with a needle-hole, a folding member at one side and in advance of the needle-hole, a substantially parallel supporting arm at the opposite side and in advance of the needle-hole, a separating member pivoted to said arm, a spring for yieldingly holding the free end portion of said separating member in normal operative position, a stop for limiting displacement of the separating member by said spring, said separating member having an end portion located above the lowest part of the presser-foot in rear thereof in the direction of feed.

6. In a hemmer for sewing machines, a presser-foot having a shank and a separate foot portion provided with a needle-hole elongated in a direction transverse the line of seam formation, means for adjusting said foot portion on the shank in the direction of the length of the needle-hole, a folding member at one side and in advance of the needle-hole, a substantially parallel supporting arm at the opposite side and in advance of the needle-hole, a separating member movably mounted on said arm in advance of the needle-hole, said separating member having an end portion located above the lower surface of the presser-foot under which a turned margin of a hem is adapted to pass.

7. In a combined hemmer and presser-foot provided with a needle-hole, a folding member having a substantially vertical edge directing wall merging into a curved and downwardly inclined deflecting wall crossing the needle-hole, an arm spaced from and parallel to the folding member, a separating member pivoted at the front end of said arm, a pin carried by said separating member between its pivot and the needle-hole, a spring mounted in said presser-foot and yieldingly urging the pin carried by the separating member upwardly, an elongated aperture provided in the arm to receive said pin, said separating member having its rear end portion located in immediate proximity

- to the needle-hole and above the lower surface of the presser-foot.
8. In a combined hemmer and presser-foot provided with a needle-hole, a folding member at one side and in advance of the needle-hole, a substantially parallel supporting arm at the opposite side and in advance of the needle-hole, a separating member yieldingly mounted on said arm in advance of the needle-hole, said separating member having an end portion located at a higher elevation than the lower surface of the presser-foot in rear thereof in the direction of feed, and a guard-finger carried by the folding member in advance of the needle-hole.
9. In a sewing machine having stitch-forming mechanism including a needle, a presser-foot having a needle-hole, means associated therewith for turning a hem, in combination with means for making the distance between stitches in the turned margin of a hem greater than the distance between stitches in the underlying body-portion of the hem whereby the fullness of a hem on a curved edge of material may be distributed among the stitches securing it in place, without folding the margin transversely.
10. In a sewing machine having stitch-forming mechanism including a needle, a presser-foot having a needle-hole, means associated therewith for turning a hem, in combination with means located within the foot proper for making the distance between stitches in the turned margin of a hem greater than the distance between stitches in the underlying body-portion of the hem whereby the fullness of a hem on a curved edge of material may be distributed among the stitches securing it in place, without folding the margin transversely.
11. In a sewing machine having stitch-forming mechanism including a needle, a presser-foot having a needle-hole, means associated therewith for turning a hem, in combination with means located within the foot proper for making the distance between stitches in the turned margin of a hem greater than the distance between stitches in the underlying body-portion of the hem whereby the fullness of a hem on a curved edge of material may be distributed among the stitches securing it in place, without folding the margin transversely.

In testimony whereof, I have signed my name to this specification.

ALBERT H. DE VOE.
